UNITED STATES PATENT OFFICE

WALTER C. MALOZ, OF NEW ORLEANS, LOUISIANA

PERPETUAL CALENDAR

Application filed January 14, 1932. Serial No. 586,624.

This invention relates to a perpetual calendar, the general object of the invention being to provide a body part having a number of windows therein arranged in an arc 5 of a circle and located above a number of transverse rows of figures, which indicate the days of the month, with a disk rotatably connected with the body part and having the days of the week printed thereon so that 10 by adjusting the disk, the days of the week can be properly arranged above the rows of figures indicating the days of the month.

Another object of the invention is to provide means whereby one can ascertain what 15 day of the week any dates of a month falls on for use in advance, and also for years in the past.

This invention also consists in certain other features of construction and in the combination and arrangement of the several parts, 20 to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a face view of the invention.

Fig. 2 is a rear view thereof.

Fig. 3 is an enlarged view of the lower part of Fig. 1.

Fig. 4 is an edge view.

Fig. 5 is a fragmentary view of the chart carried by the two reels.

Fig. 6 is a section on line 6—6 of Fig. 1.

In these drawings, the numeral 1 indicates the body of the calendar which is formed of cardboard or the like, and contains a space 20 on its front face for receiving advertising matter or the like and below this space is an arcuate row of windows 3 and below the windows is a rectangular space provided with a plurality of squares 4 which contain the days of the month as shown at 5. Below the base is a pocket 6 which contains a window for exposing the slips 7 which contain the names of the various months it of course being understood that each slip has a day of the month thereon, so that by placing the

proper slip at the front of the pocket the name of the month thereon will be exposed through the window.

A disk 8 is located at the rear of the body and is fastened to the rear end of the knob 55 9 which is rotatably arranged in the body and said disk carries the names of the days of the weeks as shown at 10, these names being so arranged that they will appear at the windows 3 as shown in Fig. 1. By rotating the disk, the names of the days of the week can be arranged in proper relation to the dates of the month.

For instance, as shown in Fig. 1, the date in the first vertical column of figures will 65 be Sunday, but if the second day of the month should come on a Sunday, the disk could be turned so as to place the Sunday indication over the second column and of course the Monday indication would come over the first column.

Lips 11 are formed on the periphery of the disk 8 for engaging a stop 12 on the rear part of the body for limiting the movement of the disk 8 and a thermometer 13 75 77 will be attached to the front of the body.

Elongated slots 14 and 15 are formed in the lower end of the body and two reels or rolls 16 are journaled in a small casing 17 and attached to the rear face of the body 80 at the lower end thereof, and the ends of a sheet 18 are fastened to these rolls. Such sheet carries the charts 19 and 20, the chart 19 having portions thereof visible through the slot 15 and the chart 20 thru the slot 14. 85 Each roll has a knob 21 attached thereto located outside of the casing so that either roll can be turned.

The chart 19 has a vertical row of figures thereon indicating years as shown at 22 and opposite each figure is a row of figures shown at 23, these figures being index numbers for indicia on chart 20. This chart 20 is divided into a plurality of vertical columns, each of which contains data indicating the days of the week as shown at 24 and opposite each week day indication is a number 25 indicating a day of the month.

The two charts are so formed, that by turning the sheet to bring any desired number 100

indicating a year into view at the slot 15 and then finding a month, a day of which is to be ascertained, for that year, through means of the month indicating characters 26 on the body above the slot 15, the index member of said month of that year can be ascertained.

For instance, if one wishes to ascertain what day of the week July 4, 1902, came on, he would turn the sheet to bring the year date 1902 into view at the slot 15 and then he would read along the characters 26 and find the letter "J" indicating July. Under this letter he would find the numeral 2. This is the index number for the chart 20 visible through the slot 14 which has the reference numerals 27 thereover. He would then turn the sheet until the numeral 4, indicating the day of the month required, appears in the slot 14 under the column number 2 which was given by the index number of chart 19, which would give Friday the 4th.

It will of course be understood that the data on chart 20 is arranged in accordance with the index numbers of chart 19. These numbers indicate the years.

A window 28 is also formed in the body above the slots 14 and 15 and a slide 29 is supported in the guide 30 at the rear of the body, so that numerals on the slide will appear through the window 28 when the slide is adjusted.

Thus it will be seen that I have provided simple means for providing a perpetual calendar with means whereby the day of a week on which falls the date of the month in past or future years can be ascertained through means of a sheet containing a chart and having data thereon indicating years and index numbers thereon and a second chart divided into columns, each space of each column containing data giving the day of the month and the day of the week arranged in accordance with the index numbers on the first chart so as to give the information desired.

It is thought from the foregoing description that the advantages and novel features of the invention will be readily apparent.

It is to be understood that changes may be made in the construction and in the combination and arrangement of the several parts provided that such changes fall within the scope of the appended claims.

Having thus described my invention, what I claim as new is:—

1. A calendar of the class described comprising a body having an arcuate row of windows therein, a disk rotatably supported at the rear of the body and having data thereon indicating the names of the days of the week for appearing at the windows, said body having on its front face the numerals indicating days of the month, each vertical column of figures on said face being arranged under a window and a pocket on the front face of the body containing slips, each of which is

marked with the name of a month, said body having a pair of aligned slots therein, rollers supported in rear of the body containing a sheet, said sheet having two charts thereon for appearing through the slots, one chart having a column of figures indicating years and a row of figures opposite each year indication forming index numerals and the body above the last-mentioned slot having indications indicating the names of the month and the other chart having columns of data thereon representing the days of the week and dates in the month.

2. A calendar of the class described comprising a body, a pair of aligned slots therein, a row of numerals adjacent one slot, data arranged adjacent the other slot indicating the month of a year, a sheet adjustably arranged at the rear of the body and divided into two charts, one of which appears at the first-mentioned slot and the other at the second-mentioned slot, the first mentioned chart being divided into columns and each column divided into spaces, each space having therein a number indicating the day of the month and characters indicating a day of the week, and the other chart having a column containing figures indicating the years and a row of figures opposite each year to serve as index characters for the data on the other chart.

In testimony whereof I affix my signature.
WALTER C. MALOZ.
